CLAIM

The ornamental design for a display screen or portion thereof with graphical user interface, as shown and described.

DESCRIPTION

FIG. 1 is a front view of a display screen or portion thereof with a graphical user interface showing our new design; FIG. 2 is a front view of a second embodiment of a display screen or portion thereof with graphical user interface showing our new design;

FIG. 3 is a front view of a third embodiment of a display screen or portion thereof with graphical user interface showing our new design;

FIG. 4 is a front view of a fourth embodiment of a display screen or portion thereof with graphical user interface showing our new design;

FIG. 5 is a front view of a fifth embodiment of a display screen or portion thereof with graphical user interface showing our new design;

FIG. 6 is a front view of a sixth embodiment of a display screen or portion thereof with graphical user interface showing our new design;

FIG. 7 is a front view of a seventh embodiment of a display screen or portion thereof with graphical user interface showing our new design; and,

FIG. 8 is a front view of an eighth embodiment of a display screen or portion thereof with graphical user interface showing our new design.

The outermost broken lines illustrate a display screen or portion thereof and form no part of the claimed design. Remaining broken lines, illustrating portions of the graphical user interface, form no part of the claimed design.
